GAS TREATING APPARATUS

Filed Aug. 15, 1929

UNITED STATES PATENT OFFICE

JULIUS GOLDSTEIN, OF BROOKLYN, NEW YORK

GAS TREATING APPARATUS

Application filed August 15, 1929. Serial No. 386,166.

This invention relates to a gas treating apparatus.

The object of the invention is the production of an apparatus, to practically separate the harmless ingredients from the harmful ingredients in the exhaust gases of internal combustion engines, such as those used for automobiles. The second object of the invention comprises means to separate the 10 harmless ingredients in the exhaust gases of internal combustion engines and which for the most part consist of carbon particles and foreign matter, from the harmful portion of the mixture, by means of mechanical separation and conducting the said harmful portion to the carburetor of the engine for reuse. The third object of the invention is the production of means and steps whereby the lighter combustible and harmful ingredients 20 of the exhaust gases of internal combustion engines are automatically separated therefrom.

The fourth object of the invention is to provide means to decrease the noise of the exhaust of internal combustion engines as it enters the muffler thereof. The fifth object of the invention comprises means and steps to decrease the injurious effects of the monoxide gas which is discharged from automobile engines. The sixth object of the invention is the production of means to prevent the back fire in an internal combustion engine, and to eliminate the odors of the exhaust.

In the accompanying drawings Fig. 1 represents a section on the line 1, 1 of Fig. 2 of a gas treating apparatus exemplifying the invention; Fig. 2 shows a top plan view of Fig. 1 partly broken away and Fig. 3 is a section of Fig. 1 on the line 3, 3.

The apparatus in this instance comprises the inclined housing designated in its entirety by the numeral 15, and is indicated as having the converging side walls 16 with the notches 17, the front connection 18 and the rear connection 20 having the nozzle 21. The front connection 18 has extending therefrom the inlet nozzle 26 for the piping 27 extending from the exhaust manifold, not shown, of the engine with which the apparatus is used. The top face of the housing is recessed as in-

dicated at 28. Piping 29 extends from the nozzle 21 and leads to the carburetor of said engine. The cover for the said housing 15 is designated in its entirety by the numeral 30. The said cover comprises the annular frame 55 having the converging side members 31, the front member 32 and the rear member 33. The members 31, 32 and 33 are recessed to fit into the recess 28. The members 31 have extending therefrom the side walls 34. 60

An upper zigzag baffle plate designated in its entirety by the numeral 35 extends downwardly from the cover 30. The baffle plate 35 comprises the legs 36 practically at right angles to the plane of the cover 30 and the enclosed legs 37. 65

The upper peak ends of the zigzag baffle plate 35 are indicated at 38 and the lower peak ends are shown at 39. The side ends of the members of the baffle plate are shown 70 at 40 and 41. The ends 40 and 41 are bedded in the walls 34 and the peak ends 38 are bedded in the side members 31 of the frame of the cover 30. When the cover 30 is cast the baffle plate 35 is placed in the mould to 75 secure the peak ends 38 and the ends 40 and 41 in place.

A lower zigzag baffle plate is designated in its entirety by the numeral 45, and comprises the legs 46 parallel to the legs 36, and the legs 47 parallel to the legs 37. At one end of the baffle plate 45 is indicated the forward longitudinal leg 48 which is bedded into the front connection 18 as indicated at 49. At the other end of the baffle plate 45 is 80 shown the rearward longitudinal leg 50 which is bedded into the connection 20 as shown at 51. The upper peak ends of the baffle plate 45 are indicated at 52 and at the lower peak ends of the baffle plate 45 are 85 formed separator openings 53. The side ends of the legs 46 and 47 are bedded in the side walls 16 of the housing 15 as indicated at 55. A zigzag passage 56 is formed between the baffle plates 35 and 45. 90

A discharge chamber designated in its entirety by the numeral 60 extends from and below the housing 15. The said discharge chamber comprises the top wall 61 having the side ends 62 which are bedded in 100

the side walls 16 of the housing 15. The rear end of the top wall 61 is bedded in the connection 20. The forward end 63 of the top wall 61 is spaced from the connection 18 by 5 being bent on itself to form the opening 65. The said bent over portion joins with the front wall 66 having the opening 67. To the top wall 61 is connected the curved bottom wall 70 having the side walls 71 with 10 the flanges 72. The latter are also bedded in the walls 16. The said bottom and side walls have formed therewith the curved nose 73 which terminates in the connection 18. The rear end of the discharge chamber 60 has 15 formed therewith the rear wall 78 having the opening 79 constituting a second outlet. A muffler pipe 80 is indicated with the outwardly extending end flange 81 and the inwardly extending flange 82. The flange 81 20 is fastened to the wall 78. An annulus 83 of crucible graphite is located in the pipe 80.

An inclined baffle plate 84 extends from the top wall 61 and at its lower end is spaced from the wall 70 to form the opening 85. A 25 second inclined baffle plate 86 extends from the wall 61 and is spaced from the wall 70 to form the opening 87. A baffle plate 88 extends from the wall 70 and is spaced from the wall 61 to form the opening 89. It is to 30 be noted that said baffle plates 84, 86 and 88 extend the full width of the discharge chamber 60.

To detachably secure the cover 30 to the housing 15 a plurality of snap connections 35 are provided. Each snap connection comprises a U-shaped member having the horizontal portion 90 and the depending legs 91 with the hook ends 92 coacting with the notches 17. A pair of curved springs 93 are 40 positioned below the portion 90 and have each one end fastened thereto by the rivets 94. A pair of latches 95 each having an arm 96 are pivoted to portion 90. Each of said latches coacts with one of the springs 93. 45 Straps 97 and 98 engage the apparatus to connect it to the vehicle for which it is used.

To use the gas treating apparatus the exhaust from the exhaust manifold of the 50 engine flows into the pipe 27 in the direction of the arrow A and enters the housing 15, wherein it flows through the zigzag passage 55. While the gases are passing therethrough they are deflected by striking the legs 36, 37, 46 and 47 of the zigzag baffle plates. Thereby the heavy portions of the mixture, which comprise carbon particles and foreign matter, drop through the openings 53, and flow downwardly in the direction 60 of the arrow B until they reach the opening 65 when they descend and enter the chamber 60. The openings 53 are positioned below the bottom turning points of the direction 65 of the flow of the gases in the zigzag 65 passage 56. The carbon particles in the gases

at these lower turning points of the flow of gases in the zigzag passage 56 automatically gravitate through the openings 53. The heavy particles with a portion of the gases then flow in the direction of the arrow C and 70 impinge against the baffle plates 84, 88 and 86. The latter baffle plates provide a check for the gases from flowing through the chamber 60. The heavy unharmed particles next 75 enter the muffler pipe 80 in the usual manner. The crucible graphite 83 in the pipe 80 diminishes the noise of the exhaust gases when they are discharged from said pipe 80.

The light and harmful gases of the mixture flow from the zigzag passage 56 80 through the rear connection 20 and enter the pipe 29 on the way to the engine to be reused.

Various modifications may be made in the invention and the present exemplification is 85 to be taken as illustrative and not limitative thereof.

Having described my invention what I desire to secure by Letters Patent and claim is:

1. In an apparatus of the character de- 90 scribed the combination of a housing having an inlet for gases to be treated, piping ex- tending from said inlet adapted to be con- nected to the exhaust manifold of an internal combustion engine, said housing having an 95 outlet, piping extending from said outlet adapted to be connected to said engine, zig- zag baffle plates in the housing spaced from each other to form a zigzag passage for the 100 gases being treated, one of said baffle plates having openings in its lower peak ends, below the lower turning points of the flow of the gases in said zigzag passage for the separation of the heavy ingredients in said gases and a discharge chamber below said openings and in connection with said passage.

2. In an apparatus of the character de- 105 scribed the combination of a housing com- prising side walls, a front connection formed with the housing, a rear connection formed 110 with the housing, piping extending from the front connection for gases to be treated, piping extending from the rear connection for gases after having been treated, a cover de- 115 tachably connected to the housing, a zigzag baffle plate depending from said cover into said housing, a zigzag baffle plate in the hous- 120 ing and spaced from the first zigzag baffle plate to form a zigzag passage for the flow of the gases being treated, the said second baffle plate having separator openings formed therethrough below the lower turn- 125 ing points of the flow of the gases in said zigzag passage and a curved wall extending from and below said housing constituting a discharge chamber, said chamber having its interior in connection with the interior of said housing.

3. In an apparatus for the treatment of ex- 130 haust gases of an internal combustion en-

gine the combination of a housing comprising side walls, a front connection at the front end of the housing, a rear connection at the rear of the housing, said front connection adapted to be connected to the exhaust appurtenances of said engine, said rear connection adapted to be connected with the carburetter of the engine, a detachable cover for said housing, a zigzag baffle plate depending from said cover into said housing, a second zigzag baffle having its sides connected to said housing and spaced from the first zigzag baffle plate, to form a zigzag passage for the flow of gases being treated, said second baffle plate having separator openings through its peaks at its bottom, a discharge chamber comprising a top wall, a bottom and side walls for the chamber spaced from its top wall, said top wall having an opening to connect the interior of the chamber and the interior of the housing, a front wall for the chamber having an opening, a rear wall for the chamber having an opening and baffle plates in said chamber, the rear wall of said chamber being adapted to be connected to a muffler pipe.

4. In an apparatus of the character described the combination of a housing having an inlet for gases to be treated and having an outlet for the gases after treatment, an upper zigzag baffle plate, having upper and lower peak ends in the housing, a lower zigzag baffle plate, having upper and lower peak ends in the housing spaced from the upper zigzag baffle plate, said baffle plates forming a zigzag passage between them for the flow of the gases treated, the lower baffle plate having openings in its lower peak ends for the separation of the heavy ingredients in the gases during the flow of the gases through said zigzag passage, said openings positioned below the bottom turning points of the direction of flow of the gases in said zigzag passage.

5. Signed at the borough of Manhattan, city of New York in the county of New York and State of New York this 14th day of August, A. D. 1929.

JULIUS GOLDSTEIN.
